Inventor
Franciszek Dudek,
By his Attorney
Adrian S. Schatz

UNITED STATES PATENT OFFICE.

FRANCISZEK DUDEK, OF JOHNSTOWN, PENNSYLVANIA.

TELESCOPIC BED.

1,323,257.

Specification of Letters Patent.

Patented Dec. 2, 1919.

Application filed June 17, 1919. Serial No. 304,908.

To all whom it may concern:

Be it known that I, FRANCISZEK DUDEK, a citizen of Poland, residing at 309 Power street, Johnstown, county of Cambria, and 5 State of Pennsylvania, have invented certain new and useful Improvements in Telescopic Beds, of which the following is a specification.

This invention has for its object the 10 provision of a bed which may be extended both laterally and longitudinally so as to be used by one or more adults or children as desired.

A further object is to provide a bed which 15 may be telescopically folded or collapsed when not in use so as to occupy a minimum of space.

These and other like objects are attained by the novel construction and combination 20 of parts hereinafter described, and shown in the accompanying drawings, forming a material part of this disclosure and in which—

Figure 1 is a top plan view showing a bed 25 frame made in accordance with the invention, extended at full length.

Fig. 2 is an end view of the same.

Fig. 3 is a fragmentary end view showing the connecting elements in a partially extended position.

30 Fig. 4 is a similar view of the same, showing the parts further extended, preparatory to folding.

Fig. 5 is an enlarged longitudinal sectional view taken through the end connecting elements, and

Fig. 6 is a side elevational view showing the complete frame of the bed in a folded position.

Referring to the drawings in detail, the 40 numeral 10 designates the tubular corner posts or legs, all of which are alike and furnished at their bottoms with enlarged rounded contacts 11, taking the place of ordinary casters, knobs or like ornamental devices 12 being attached at their upper ends.

Rigidly engaged with the diagonally opposite corner posts are tubular side bars 14, the same being telescopically received by 50 larger tubular bars 15 attached to the diagonally opposite corner posts, the smaller bars being receivable within the larger. The bars 15 have lateral slots into which the

extensions 16, formed near the ends of the bars 14 operate so as to prevent the bars 55 from being completely disengaged when extended.

Another pair of legs 17 are provided with transverse heads 18 at their upper ends, which are rotatably engaged upon the bars 60 16 midway in their length. These legs 17 are provided with sleeves 19 at their lower end, containing slots 20 so that they may be raised and engaged with the opposite frame bars 14, when the bed frame is in a collapsed 65 position.

Between each pair of the corner posts 10, at the head and foot are pairs of forks 21, pivoted on pins 22, these forks being engaged with tubular elements 23, normally 70 extending horizontally toward each other, one of each pair of the elements containing screw threads receptive of the threaded ends 24 of rods 25, the smooth, opposite ends of which slidably engage in the oppositely disposed elements 23; circumjacent to the tubular elements 23 are other pairs of tubes 26 arranged in two uniform sections and connected by the hinges 27.

Formed through the walls of the outer 80 tubes 26 are slotted openings 28 and 29, engageable in which are spring actuated detents 30, secured in recesses formed in the inner tubes 23, the arrangement being such that when the detents 30 are engaged with 85 the openings 29, the parts are held closely together, while, if the parts be separated, the detents will engage in the openings 28, thereby holding the parts locked in spaced 90 relation, at which time the joints may be broken on the hinges 27, the rods 25 at that time being retracted from the center, while obviously, when in a closed position and the detents are in the openings 29, the joints cannot be broken upon the hinges due to the 95 effect of the rods 25.

From the foregoing it will be seen that a substantial and practical embodiment of a tubular bed frame has been presented which will be found a convenient adjunct for 100 household purposes, as it may be so expanded for the use of two or more persons, or shortened in length so that it will accommodate children or, when not required for use, be so folded as to be disposed in a small 105 space.

Having thus described my invention and set forth the manner of its construction, application and use what I claim as new and desire to secure by Letters Patent, is—

- 5 1. In a telescopic bed, the combination with the corner posts thereof, tubular bars extending from diagonally opposite corners, telescopic elements formed from the other opposite corners engageable with said tubular bars, means for preventing the separation of all of said elements, and an auxiliary pair of legs engaged with said telescopic elements adapted to be turned so as to engage with said tubular bars when the bed is in a 15 folded position so as to hold the same together.
- 10 2. In a telescopic bed, the combination with the corner posts thereof, telescopic frame elements extending longitudinally therebetween, a secondary pair of legs carried on said telescopic elements, and means for limiting the ultimate movement of said telescopic elements, of pairs of cross elements extended between said pairs of corner 15 posts, said cross elements being pivotally engaged with the posts, and consisting of

telescopic elements, stiffening rods in said telescopic elements, sectional tubes enveloping said telescopic elements, hinges connecting the sections of said tubes at their center, 30 and means for holding said tubes when in an extended or retracted position, said elements when in a fully extended position being adapted to fold upon said hinges.

3. In a telescopic bed, the combination 35 with the four posts thereof, and connections extending from side to side between said posts, of pairs of sectional connections between each pair of posts at the head and foot thereof, rods rigidly engaged in one 40 section of said connections extending into the other of sections, tubes surrounding said connections, said tubes being formed in sections, hinges connecting the sections together, and means formed with said telescopic elements for engaging said tubes whereby they may be held in either an extended or retracted position.

In testimony whereof I have affixed my signature.

FRANCISZEK DUDEK.
